UNITED STATES PATENT OFFICE.

JARVIS E. KELSEY, OF WEST HAVEN, CONNECTICUT, ASSIGNOR TO THE
WEST HAVEN BUCKLE COMPANY, OF SAME PLACE.

MACHINE FOR MAKING BUCKLES.

SPECIFICATION forming part of Letters Patent No. 339,899, dated April 13, 1886.

Application filed March 1, 1886. Serial No. 193,595. (No model.)

To all whom it may concern:

Be it known that I, JARVIS E. KELSEY, of West Haven, in the county of New Haven and State of Connecticut, have invented a new Improvement in Machines for Making Buckles; and I do hereby declare the following, when taken in connection with accompanying drawings and the letters of reference marked thereon, to be a full, clear, and exact description of the same, and which said drawings constitute part of this specification, and represent, in—

Figure 1, a top view of the apparatus below the upper die, G; Fig. 2, an under side view of the upper die, G; Fig. 3, a vertical section of the lower die cutting through one of the recesses b, and showing a side view of the upper die and of the follower M; Fig. 4, a front view of the lower die, showing the recesses b; Fig. 5, the frame as bent preparatory to the operation of this apparatus; Fig. 6, an end view of the frame, showing the first operation; Fig. 7, the same, showing the second operation of this apparatus; Fig. 8, an end view of a buckle complete; Fig. 9, a face view of the buckle complete.

This invention relates to an improvement in apparatus for manufacturing that class of buckles in which the frame is made from a piece of wire bent into nearly U shape, the tongue portion, also made from a single piece of wire bent to form a loop in the central portion, and the two ends turned therefrom to form the tongues, the two ends of the frame bent around the tongue portion to form the hinge between the two parts, the buckle being well known as the "Hartshorn" buckle, the invention being adapted to the manufacture of the frame part of the buckle.

In Fig. 5 a single frame is shown as bent preparatory to the operation which it is proposed to perform by this invention. This is made from a piece of wire bent to form the bearing-bar A, turned at its two ends to form the rounded ends B B of the frame, the end portions C C turned therefrom at right angles to the bearing-bar A, and distant from each other less than the extreme length of the frame. The two legs C C are to form the hinge portion of the frame, and are bent around the tongue portion.

The object of this invention is to strike the frame, and so as to flatten and shape the bearing-bar, as indicated in broken lines, Fig. 5, and to bend the legs into shape to be readily clasped upon the tongue portion, such shape being indicated in Fig. 7, and so that when the hinge is completely formed, as seen in Figs. 8 and 9, the tongue portion will be in substantially the plane of the frame; and the invention consists in the construction of the apparatus whereby the frame is shaped, as herein-after described, and more particularly recited in the claim.

The apparatus is arranged in a common power-press, and in the illustration I show only the bed D and the slide E of the press, it being understood that the bed is stationary, and the slide actuated in the usual manner, to reciprocate toward and from the bed, the mechanism for operating the slide being too well known to require illustration. On the bed a die, F, is fixed below the slide. The upper surface of this die is plain and flat, except at the front or forward edge is a raised rib, a. The rib is of a rounded shape, corresponding to the bend required in the legs of the frame. In the front of the die two cavities, b b, are made directly below the rib a, and so that the rounded shape of the rib continues into these recesses. The recesses are distant from each other corresponding to the legs of the frame to be bent, and so that as the frames are successively passed forward onto the die, as illustrated in Fig. 1, the two legs C C of the frame will project over the rib a, and at points corresponding to the recesses b b in the front of the die, as indicated in Fig. 3.

G is the movable die, which is fixed in the slide E in the usual manner. Longitudinally across its under face is a recess, e, corresponding to the exterior of the bend required in the legs, and forward of the recess the die projects downward, as at f, below the face of the die G. On the face of the die G a cavity is formed, as indicated in Fig. 2, corresponding to the finished shape of the body part of the frame, and of the usual shape for this class of buckles.

When the frame is placed upon the lower die, with its legs projecting over the rib a, as seen in Figs. 1 and 3, the slide descends, bringing the die G down upon the frame, the recess

causing the body of the frame to come down upon the face of the die F, back of the rib a, and the projection f turns the legs straight downward. This operation shapes the body 5 of the frame and brings the legs into the shape indicated in Fig. 6, the bend of the legs being above the plane of the frame. As this bend is made, the two legs stand forward of the recesses b b below the rib.

10 During the last part of the descent of the slide E a horizontal slide, H, is actuated by the slide E—say as by a cam, I, fixed to the slide E—acting upon the slide H, through a post, L, thereon, and so that an inward movement is imparted to the slide H during the 15 said last part of the descent of the slide E. The slide H carries a follower, M, in the plane of the recesses b b in the front of the die F, and so that as the follower M advances, under the 20 movement of the slide H, two projections, h, on the inner end of the follower M will impinge upon the downwardly-projecting portion of the legs of the frame and bend them into the recesses b b, as indicated in broken 25 lines, Fig. 2, and complete the bend of the legs, as shown in Fig. 7. By this operation the frame is shaped and the hinge portion of the

legs bent into a convenient shape to be turned around the tongue portion, as indicated in Figs. 8 and 9, and such bend being both above 30 and below the plane of the frame, brings the tongue substantially into the plane of the frame, as indicated in Fig. 8, the shaping of the frame and such bending of the legs being performed at a single operation. 35

I claim—

The combination of the fixed die F, constructed with a longitudinal upwardly-projecting rounded rib, a, at its front edge, with recesses b b on the front, below said rib, the 40 corresponding die, G, having in its face a cavity corresponding to the finished shape of the frame, and with a longitudinal recess, e, corresponding to the rib a, and also with a downward projection, f, forward of said recess e, 45 with the horizontally-reciprocating follower M, constructed with projections h h, corresponding to said recesses in the front of the die F, substantially as and for the purpose described.

JARVIS E. KELSEY.
